The ornamental design for a disk recording/reproducing apparatus, as shown and described.

DESCRIPTION

FIG. 1 is a top plan view of disk recording/reproducing apparatus showing our new design;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a front view of thereof, with power turned on.

FIG. 1

FIG. 2

FIG. 3

FIG. 4
